CLAIM

The ornamental design for a brush, as shown and described.

DESCRIPTION

FIG. 1 is a perspective view of a first embodiment of a brush showing the new design;
FIG. 2 is a front view thereof;
FIG. 3 is a rear view thereof;
FIG. 4 is a right side view thereof;
FIG. 5 is a left side view thereof;
FIG. 6 is a top view thereof;
FIG. 7 is a bottom view thereof;
FIG. 8 is a perspective view of a second embodiment of a brush showing the new design;
FIG. 9 is a front view thereof;
FIG. 10 is a rear view thereof;
FIG. 11 is a right side view thereof;
FIG. 12 is a left side view thereof;
FIG. 13 is a top view thereof;
FIG. 14 is a bottom view thereof;
FIG. 15 is a perspective view of a third embodiment of a brush showing the new design;
FIG. 16 is a front view thereof;
FIG. 17 is a rear view thereof;
FIG. 18 is a right side view thereof;
FIG. 19 is a left side view thereof;
FIG. 20 is a top view thereof;
FIG. 21 is a bottom view thereof;
FIG. 22 is a perspective view of a fourth embodiment of a brush showing the new design;
FIG. 23 is a front view thereof;
FIG. 24 is a rear view thereof;
FIG. 25 is a right side view thereof;
FIG. 26 is a left side view thereof;
FIG. 27 is a top view thereof; and,
FIG. 28 is a bottom view thereof.

The brush bristles, illustrated in broken lines throughout the drawings, form no part of the claimed design. The dash-dot-dash break lines in FIGS. 8, 11-13, 22, and 25-27 are shown with a symbolic break in its length; the appearance of any portion of the article between the break lines forms no part of the claimed design. The single dash-dot-dash broken line extending along the brush in FIGS. 8, 11, 12, 22, 25, and 26 and across the brush in FIGS. 14 and 28 represents a
